CLAIM

The ornamental design for a brake housing, as shown and described.

DESCRIPTION

FIG. 1 is a top, rear, left side perspective view of a brake housing showing the claimed design;

FIG. 2 is a bottom, front, right side perspective view showing the claimed design;

FIG. 3 is a front elevational view showing the claimed design;

FIG. 4 is a rear elevational view showing the claimed design;

FIG. 5 is a left side elevational view showing the claimed design;

FIG. 6 is a right side elevational view showing the claimed design;

FIG. 7 is a top plan view showing the claimed design; and,

FIG. 8 is a bottom plan view showing the claimed design. The broken lines in the drawings illustrate portions of the brake housing that form no part in the claimed design.
